CLAIM

The ornamental design for a vehicle inspection system support structure as shown and described.

DESCRIPTION

FIG. 1 is a front perspective view of a vehicle inspection system support structure showing our new design;

FIG. 2 is a rear perspective view of a vehicle inspection system support structure;

FIG. 3 is a front view of the vehicle inspection system support structure;

FIG. 4 is a rear view of the vehicle inspection system support structure;

FIG. 5 is right side view of the vehicle inspection system support structure;

FIG. 6 is left side view of the vehicle inspection system support structure;

FIG. 7 is a top view of the vehicle inspection system support structure; and,

FIG. 8 is a bottom view of the vehicle inspection system support structure.

The broken lines shown within the drawings illustrate features that form no part of the claimed design.

1 Claim, 6 Drawing Sheets
